UNITED STATES PATENT OFFICE.

ANDREW SIVERTSON, OF AUBURNDALE, WISCONSIN.

SHINGLE-GUIDE.

SPECIFICATION forming part of Letters Patent No. 723,746, dated March 24, 1903.

Application filed October 6, 1902. Serial No. 126,103. (No model.)

To all whom it may concern:

Be it known that I, ANDREW SIVERTSON, a citizen of the United States, residing at Auburndale, in the county of Wood and State 5 of Wisconsin, have invented certain new and useful Improvements in Shingle-Guides, of which the following is a specification.

My invention relates to shingle-guides; and it consists of a collapsible straight-edge to 10 which is secured a clamping mechanism whereby said straight-edge is held in proper position for work.

The object of my invention is to dispense with the usual nail-guide and apparatus and 15 produce a guide that is simple, effective, compact, and cheap of manufacture.

A further object of my invention is to produce a device of this character that is easily and readily attached and detached to and 20 from the work; and with these objects in view my invention consists of the parts and combinations of parts, as will be hereinafter more fully set out.

In the drawings, Figure 1 is a perspective 25 view of the device in folded position. Fig. 2 is a top plan view of the same in extended position. Fig. 3 is a side elevation of my invention in use.

1 and 2 are hinged members, preferably 30 pivoted together at their ends, so as to form in open position an elongated guide. These members 1 and 2 are each provided with a flange 3 at right angles thereto, said flanges forming straight edges throughout the length 35 of the device upon which the butt of the shingle may rest. While I have shown lugs 4 and 5 of the respective members 1 and 2 as in merely frictional relation with each other, it is of course obvious to those skilled in the 40 art that I may provide any suitable locking device, such as serrations, whereby the parts may be positively locked in extended or closed position. As the serrations in a joint of this character are old, it is not deemed necessary 45 to illustrate them in the drawings.

6 is a locking-plate provided with an elongated slot 7, in which a bolt 8 is secured, said bolt being also secured to the straight-edge member 2. The object of the elongated slot 50 is to adapt said plate 6 for adjustment in order that different "weathers" may be given to the shingles. The bottom of this plate is

somewhat wider than the main body thereof and terminates in two arms 9, said arms being pointed and bent downward at right angles and then inward parallel with the main body of the plate, thereby forming substantially U-shaped clamps on the ends of each of said arms. Said plate 6 is provided with an opening 10, on each side of which are upwardly-projecting lugs or ears 11. 12 is a locking-lever pivoted by means of the pivot 13 in the opening 10 between said ears. The upper end of this lever is provided with an operating-handle 14, while the lower end is 60 provided with spurs 15, said spurs adapted to be projected when the lever is operated through the opening 10 and into the shingle below said plate, thereby locking the entire device in position.

The operation is as follows: One row of shingles having been laid, the plate 6 is set to the desired guide by means of the elongated slot 7 and the bolt 8 and the U-shaped fastening-arms 9 pressed over the butt-end of the 75 shingle. The straight-edge members 1 and 2 having been extended, the lever 12 is pushed upward toward the straight-edge, thereby forcing the spurs into the face of the shingle, and inasmuch as the spurs are mounted and inclined eccentrically to the pivot of the lever 80 they act in the nature of a cam and draw the U-shaped ends of the arms 9 snug against the butt-end of the shingle, and as they exert a strain opposite to that of the U-shaped arms the whole device is locked securely in 85 position upon the shingle. The next row of shingles is now placed in position and is given the proper gage by merely resting the butt-end upon the straight-edge.

From the above it will be seen that I have produced a very desirable gage of this character.

It will be seen from Fig. 1 that the members 1 and 2 are folded together and that the 95 plate and locking-lever are slid by means of the elongated slide in said plate within the folded portions, so that there is very little projection beyond said members, thus forming a compact and readily-transported tool.

Having thus described my invention, what I claim as new therein, and desire to secure by Letters Patent, is—

1. In a shingle-gage, the combination with

a collapsible straight-edge, of a locking-plate and lever having a slotted connection with said-edge, and constructed to slide and fold substantially within the lines of the folded 5 straight-edge.

2. In a shingle-gage, the combination with an elongated straight-edge, of a plate adjustably secured thereto, and having clamps at its bottom edge, adapted to embrace the butt-end of a shingle, and a lever connected to said plate and adapted to pierce the shingle and draw the plate up snug against the butt-end of the shingle to lock the plate to the shingle.

15 3. In a shingle-gage, the combination with two hinged members, and a straight-edge secured at right angles to the top thereof, of a locking-plate provided with an elongated slot,

by means of which it is adjustably secured to one of said members, U-shaped clamps at the 20 bottom of said plate, constructed to engage the butt-end of a shingle, an opening in said plate intermediate the elongated slot and U-shaped clamps, a lever pivoted in said opening, and spurs secured to the bottom of 25 said lever, constructed to pierce the face of a shingle, and exert pressure in opposition to the U-shaped clamps, whereby the whole device is firmly secured in position.

In testimony whereof I have affixed my signature in presence of two witnesses.

ANDREW SIVERTSON.
